UNITED STATES PATENT OFFICE.

ALFRED L. SOHM, OF CHICAGO, ILLINOIS.

TIME-INDICATING SYSTEM.

1,394,647.

Specification of Letters Patent. Patented Oct. 25, 1921.

Application filed February 24, 1920. Serial No. 360,926.

To all whom it may concern:

Be it known that I, ALFRED L. SOHM, a citizen of the United States, and a resident of Chicago, in the county of Cook, State 5 of Illinois, have invented certain new and useful Improvements in Time-Indicating Systems, of which the following is a specification.

My invention relates to time indicating 10 systems and particularly to improved control by a master clock of an electrical secondary circuit and secondary units therein.

In time indicating systems to which my invention relates an electro-magnetically 15 wound master clock controls the opening and closing of a circuit with which are connected the secondary units which are to be wound or set by means of electro-magnets. It is practically impossible to accurately and 20 efficiently control a secondary unit circuit directly by contacts operated by the master clock mechanism. No matter how carefully the contact mechanisms are constructed double or false contacts are likely to occur 25 and the more sensitive units in the secondary circuit may respond to such irregular contacts and move forwardly, while less sensitive units would not respond, and the result would be non-synchronization and disorganization of the system.

One of the important objects of my invention is to indirectly control the secondary circuit through a relay, which relay is so constructed and so connected with the 35 master clock and the secondary circuit that it will close the secondary circuit at the regular predetermined time intervals and keep it closed during critical periods when false circuit control might otherwise emanate 40 from the master clock, the arrangement preventing the sending of more than one impulse through the secondary circuit for each time interval for which the master clock is adjusted.

45 The invention also covers improved contact mechanism, construction and arrangement in the master clock for controlling the operation of the relay.

The above and other features of my invention are incorporated in the structure and combination shown on the accompanying drawings in which drawings—

Figure 1 is a side elevational view of the master clock.

55 Fig. 2 is a front elevational view from plane 2—2, Fig. 1 and showing also the cir-

cuit connections between the master clock, relay, and secondary circuit.

Fig. 3 is a fragmentary rear elevational view to show the operation of the main 60 spring winding mechanism, and

Figs. 4 to 8 inclusive show progressive positions of the master clock contact members.

The supporting frame for the operating 65 mechanisms of the master clock comprises the base 10, the front and rear plates 11 and 12 and the upper spacing members 13. Journaled in the front and rear plates is the minute arbor for supporting the minute 70 hand 15, the hub 16 supporting the hour hand 17 being connected through a train of gears 18 with the minute arbor. On the arbor 14 is secured the gear 19 which meshes with the pinion 20 on the center arbor 21. 75 On this arbor is secured the gear 22 which meshes with the pinion 23 on the escapement arbor 24 which carries the escapement wheel 25 engaged by the escapement beam 26 supported on the upper arbor 27. A lug 80 28 extending rearwardly from the plate 12 supports the spring link 29 on which is hung the pendulum rod 30 carrying at its lower end the pendulum weight 30', the actuating rod 31 being secured to the arbor 85 27 and connecting at its lower end with the pendulum in the well known manner.

Secured to the minute arbor 14 adjacent the gear 19 is the barrel 32 containing the main spring 33, one end of this spring being 90 secured to the barrel and the other end being secured to the ratchet frame 34 rotatable on the arbor adjacent the spring barrel. The ratchet frame (Fig. 3) has the ratchet teeth 35 engaged by the pawl 36 which is 95 pivoted at its elbow on the plate 37, which plate is connected at its lower end with the armature 38 hinged at its front to the base 10. The vertical movement of the plate 37 is guided by means of the slot 39 which 100 receives the grooved collar 40 secured to the minute arbor. A spring 41 connecting between the plate and the pawl tends to hold the pawl point against the ratchet wheel. Pivoted on the plate 12 above the ratchet 105 wheel is the lock pawl 42 held by a spring 43 against the ratchet wheel. A spring 44 connecting between the armature and the plate 12 tends to hold the armature up above the ends of the cores 45 and 46 of the electro- 110 magnet structure E, which cores project upwardly through the base plate 10. When-

ever the electro-magnet structure is energized by the flow of current through its winding *w* the armature 38 is attracted and swung downwardly and during such downward swing the lock pawl 42 holds the ratchet wheel 34 while the plate 37 which moves downwardly with the armature carries the pawl 36 past a ratchet tooth so that when the armature is released and restored to the upper position the ratchet wheel will be rotated and the main spring wound up correspondingly.

The contact mechanism operated by the master clock comprises the contact wheel 47 and the contact levers 48 and 49 co-operating therewith to close circuits to be described later. The contact wheel is secured on the arbor 21 and is therefore in electrical engagement with the frame-work of the clock. The wheel has eight contact points a^1 to a^8 inclusive. In the particular structure shown, this number of contact points together with the dimensions of the gearing train between the arbor 21 and the arbor 14 causes closure of the secondary unit circuit once every minute, as will be fully explained in detail later.

The contact lever 48 is secured on the arbor 50 journaled in the plates 11 and 12 to be thus adapted to swing in the plane of the contact wheel 47. Near its upper end the lever carries a contact plate 51 insulated therefrom and connected with the conductor 52 also carried by and insulated from the lever. The weight extension 53 on the lever tends to swing it toward the contact wheel. The stop post 54 limits the outward swing of the lever.

Adjacent the free end of the armature a kick-off lever 55 is pivoted intermediate its ends in the lugs 56 on the plate 10. The inner end of the lever extends below and in the path of the armature while its upstanding outer end 57 is adjacent the arm 58 extending downwardly from the arbor 50 on which the lever 48 is secured. The arrangement is clearly shown in Fig. 3. When the armature is swung suddenly downwardly upon energization of the electro-magnet, the lever end 57 will strike the arm 58 and the contact lever will be suddenly swung laterally away from the contact wheel to disengage and hold its contact 51 from the contact wheel teeth.

Above the contact wheel and pivoted at its right end of the front plate 11 is the latch pawl 59, this pawl near its outer end and in its under side having the outer and inner abutment steps 60 and 61. These steps serve to receive the upper end of the contact lever 48. When this end is in engagement with the inner step 61 the contact plate 51 will be in the path of the contact wheel teeth and when the lever is held outwardly by the outer step 60 the contact

plate will be away from the path of the contact wheel teeth. The latch pawl has the pointed heel 62 in the path of the contact wheel teeth which serves a double purpose. First it acts as an abutment whose engagement with the contact tooth will cause sufficient upward swing of the latch pawl to release the contact lever from the outer step and permit it to swing against the inner step; and secondly the pointed heel by its engagement with a contact wheel tooth serves to clean the tooth preparatory to its electrical contact with the plate 51. Above the contact plate 51 the lever 48 has the overhanging portion 63 terminating in the sharp edge 64 just in advance of the contact plate, the purpose of the overhanging portion and edge being to clean a contact wheel tooth just before it reaches the plate, and also to swing the lever 48 a distance outwardly so that when the contact wheel tooth leaves the edge 64 the lever will be thrown with its contact plate against the contact tooth, thus further insuring good electrical contact. Each contact wheel tooth is thus cleaned twice before engaging with the contact lever and engagement of the contact teeth with the heel 62 and overhanging part 63 also cleans these surfaces preparatory to their cleaning engagement with succeeding contact wheel teeth.

The contact lever 49 is pivoted on the arbor 65 extending between the plates 11 and 12 and the lever is adapted to swing in the plane of the contact wheel 47, its weight projection 66 tending to swing the lever toward the contact wheel. At its upper end it carries the contact plate 67 insulated therefrom and connected with the conductor 68 carried by and insulated from the lever. A stop pin 69 limits the outward swing of the lever beyond the influence of its weight projection 66. The pin 70 limits the inward swing of the lever. Just in advance of the contact plate 67 the lever has secured on its front edge the cleaning lug or guard 71 along which the contact wheel teeth travel to be cleaned before being engaged by the contact plate 67 as the lever is swung inwardly when the guard lug is released from the tooth.

Referring to Fig. 2, R represents a relay interposed between the master clock and the secondary circuit S with which are connected the various secondary units *s*. The relay is shown diagrammatically but its detailed construction is disclosed in my Patent No. 1,302,604 dated May 6th, 1919. Briefly describing the relay it comprises the circuit closing electro-magnet 72 having the winding 73, and the unlocking electro-magnet 74 having the winding 75. The electro-magnet 72 has the armature 76 adapted when attracted to engage with the contact 77. The armature 78 for the electro-magnet 74 has

- the latch arm 79 terminating in the latch end 80, a spring 81 tending to swing the armature 78 to hold the latch end in the path of the armature 76 so that when its armature 5 is attracted it will glide past the latch end and be locked thereby in engagement with its contact 77 until the electro-magnet 74 is energized and its armature attracted to raise the latch.
- 10 The master clock has the shelf 82 extending therefrom for supporting the terminal posts 83, 84 and 85 and the terminal post 86, the last mentioned post being in electrical connection with the frame-work of the 15 master clock and thereby always in electrical engagement with the contact wheel 47, while the other three terminal posts are insulated from the frame-work. The post 83 is connected through conductor 87 with the conductor 52 leading to the contact plate 51. The contact post 84 is connected by conductor 88 with the conductor 68 leading to the contact plate 67 of lever 49. The electro-magnet windings w are connected in series 20 and their free terminals connect respectively with the binding posts 85 and 86. The binding post 83 is connected by conductor 89 with one terminal of the winding 73, the other terminal of which connects with the 25 contact 77 and with one pole of the battery B. The other pole of the battery connects with the limb 90 of the secondary circuit whose other limb 91 connects with the armature 76. The binding post 84 is connected 30 by conductor 92 with one terminal of the winding 75 whose other terminal is connected by conductor 93 with the limb 91 of the secondary circuit. The binding posts 85 and 86 are connected by conductors 94 35 and 95 respectively with the limbs 91 and 90 of the secondary circuit so that the electro-magnet windings w are in bridge of such circuit.
- 40 Figs. 4 to 8 clearly show the cycle of operation. The contact wheel rotates in the direction indicated by the arrow thereon. In Fig. 4 the contact tooth a^1 is traveling toward the contact plate 51, the detent pawl 59 holding the lever 48 out by its outer step 50 50. The contact tooth a^2 is just about to engage with the heel of the latch pawl and the tooth a^5 is approaching the lug 71 on the lever 49. Both electro-magnets of the relay R are deenergized and the armature 76 is 55 in its open circuit position as indicated by dotted lines Fig. 2. As the contact wheel rotates, the tooth a^2 will engage with the heel 62 of the latch pawl to raise the pawl sufficiently to permit the lever 48 to swing 60 into engagement with the inner step 61 to thereby carry its contact plate 51 into the path of the on-coming tooth a^1 . The tooth a^5 is just coming into engagement with the lug 71 on lever 49, all as shown in Fig. 5. 65 The next position of the parts is shown in
- Figs. 2, 4 and 6. The tooth a^2 has left the latch pawl to leave it free to rest on the lever 48, and the tooth a^1 has just wiped across the overhang portion 63 and its point 64 and is in engagement with the contact 70 plate 51. The tooth a^5 is at the end of the lug 71. As soon as the tooth a^1 contacts with the plate 51 circuit is closed through the winding 73 of the relay electro-magnet 72, the circuit being traced as follows: battery B, winding 73, conductor 89, post 83, conductor 87, conductor 52 and contact plate 51, contact wheel 47, clock frame and post 86, and conductor 95. Upon closure of this circuit the armature 76 is attracted into engagement with the contact 77 to close the secondary circuit S which will then be supplied with current from the battery B, and all the secondary units s and also the electro-magnet E of the master clock will be energized. Immediately upon energization of the master clock electro-magnet, its armature is drawn down and the kick lever 55 is struck thereby and rotated to engage the arm 58 on the arbor 50 so that the contact lever 48 is swung away from the contact wheel, as indicated in dotted lines Fig. 6. The lever weight 53 then swings the lever inwardly but the lock pawl is in the way and its step 60 receives the lever to hold its contact plate out of the path of the contact wheel teeth, as indicated in Fig. 7. Swinging away of the contact lever from the contact wheel will of course open the circuit just traced through the electro-magnet winding 72, but immediately when the armature of this electro-magnet was drawn up the latch end 80 received it and locked it against its contact 77 so that closure of the secondary circuit is maintained. After opening of the circuit by swinging away of the contact lever the contact wheel tooth a^5 still has some distance to travel along the lug 71 and this gives the contact lever a chance to become firmly established in its position in engagement with the outer step of the detent pawl. Even though the contact lever should miss the pawl or be jarred loose, and engage with the contact wheel during engagement of the tooth a^5 with the lug 71, it could not cause false impulse through the secondary circuit on account of the locking of the circuit in closed condition by the latched armature 76. 105 After the contact tooth a^5 leaves the lug 71, the contact plate 67 will be carried against the tooth by the lever 49 and circuit will be closed through the winding 75 of the relay electro-magnet 74, this circuit including the armature 76 and its contact 77. The circuit is traced as follows: battery B, contact 77, armature 76, conductor 93, winding 75, conductor 92, post 84, conductors 88 and 68, contact plate 67, contact wheel 47, clock frame and post 86, and conductor 95. Upon energization of the elec- 110 115 120 125 130

tro-magnet 74 its armature 78 is attracted and the lock lever 79 raised to release the armature 76 so that the secondary circuit is opened. The contact engagement between 5 the tooth a^5 and the contact plate 67 is of sufficient duration to give the unlocking electro-magnet ample time to perform its unlocking work. When the tooth leaves the contact plate the electro-magnet 74 is de- 10 energized and its armature released to permit the latch point 80 to again position itself in front of the retracted armature 76 ready for the next locking operation. After engagement of the tooth a^1 with the contact lever 48 and engagement of the tooth a^3 with the contact lever 49, the next tooth a^2 will coöperate with contact lever 48 and the tooth a^6 with the lever 49, and the cycle 15 of operations will be repeated.

20 96 represents a non-inductive resistance connected with the binding posts 85 and 86 to be in bridge of the electro-magnet windings w . This resistance will take care of the counter-current generated when the 25 electro-magnet circuit is broken.

30 My improved construction, arrangement and operation is very substantial and efficient. The secondary circuit which controls the synchronization of time at the various 35 units and the winding thereof is kept closed during the critical period when irregular and false current impulses would tend to occur. Disorganization of a time indicating system is therefore fully guarded 35 against.

Having described my invention, I claim as follows:

1. In a time indicating system, the combination of a master clock comprising a 40 clock train, a contact wheel connected to be driven by said train, an electro-magnet associated with said clock, a secondary circuit with which said electro-magnet is connected, a main contact lever associated with 45 said contact wheel, means controlled upon engagement of said lever with said wheel for closing said secondary circuit, locking means controlled upon first closure of said circuit for locking said circuit closed independently of said lever and wheel, said magnet being adapted upon closure of such 50 circuit to release said lever from said wheel to thereby open the circuit at such point, a second contact lever associated with said 55 contact wheel electro-magnetic unlocking means and a circuit therefor, engagement of said second contact lever with said contact wheel causing closure of said unlocking means circuit and actuation of said unlocking 60 means to open said secondary circuit.

2. In a time indicating system, the combination of a master clock, a contact wheel driven by the clock train, an electro-magnet associated with said clock, a secondary circuit with which said electro-magnet is con-

nected, a contact lever associated with said contact wheel, a relay, a circuit for said relay closed upon engagement of said contact lever with said contact wheel, contacts controlled upon energization of said relay 70 for closing said secondary circuit, means for locking said contacts together to maintain closure of said secondary circuit, means whereby energization of said electro-magnet upon closure of said secondary circuit will 75 cause disengagement of said contact lever and contact wheel whereby to open said circuit, a second contact lever associated with said contact wheel, an unlocking electro-magnet and a circuit for said unlocking 80 electro-magnet closed upon engagement of said second contact lever with said contact wheel, said unlocking electro-magnet actuating said locking means to cause unlocking of said contacts and reopening of 85 said secondary circuit.

3. In a time indicating system, the combination of a master clock, a contact wheel driven by the clock train, a contact lever associated with said contact wheel, a relay, a circuit for said relay adapted to be closed when said contact lever engages with said contact wheel, contacts for said relay, a secondary circuit closed by said contacts when said relay circuit is closed, an electro-magnet 90 associated with said clock and connected with said secondary circuit to be energized upon closure thereof, means actuated upon energization of said electro-magnet for releasing said contact lever from said contact wheel to open the relay circuit at said point, locking means for locking the relay contacts to keep the secondary circuit closed immediately after first closure of said relay circuit, electro-magnetic unlocking means, a 95 circuit for said unlocking means, and a second contact lever associated with said contact wheel to close said unlocking means, circuit to cause actuation thereof to control the locking means to unlock said relay contacts 100 and thereby reopening of the secondary circuit.

4. In a time indicating system, the combination of a master clock, a contact wheel driven by the clock train, a contact lever adapted to periodically engage with said contact wheel, a relay, a circuit for said relay controlled by said contact lever and wheel, a secondary circuit closed by said 115 relay when the relay circuit is first closed, means for locking said relay to maintain closure of said secondary circuit independently of said contact lever and wheel, an electro-magnet associated with said contact lever and connected with said secondary circuit, 120 energization of said electro-magnet causing release of said contact lever from said wheel to open the relay circuit at that point immediately after closure of said circuit, a second contact lever associated with said con- 125

tact wheel, an unlocking electro-magnet for unlocking said relay to permit reopening of the secondary circuit, and a circuit for said unlocking electro-magnet controlled by said 5 contact wheel and second contact lever, said circuit including the relay contacts.

5. In a time indicating system, the combination of a master clock, a contact wheel driven by the clock train, a contact lever associated with said contact wheel and adapted 10 to periodically engage therewith, a relay, a circuit for said relay closed upon engagement of the contact lever with said wheel, contacts for said relay closed upon energization 15 thereof, a secondary circuit connected with said contacts, an electro-magnet connected with the secondary circuit and adapted upon energization to withdraw said contact lever from the contact wheel to open the 20 relay circuit at that point, locking means for locking the relay contacts immediately upon first closure of said relay circuit whereby to maintain closure of the secondary circuit independently of said contact lever and wheel, 25 a second contact lever associated with said contact wheel, an unlocking electro-magnet for unlocking said relay contacts to permit reopening of the secondary circuit, an ener-

gizing circuit for said unlocking electro-magnet, said second contact lever and wheel 30 coöperating to close the circuit for the unlocking electro-magnet after a period of closure of the secondary circuit by the locked relay contacts.

6. In a time indicating system, the combination of a master clock, a relay, an energizing circuit for said relay, contact mechanism controlled by the clock train to periodically close said relay circuits, a secondary circuit closed by said relay upon energization thereof, means for locking said secondary circuit closed independently of said clock contact mechanism, an unlocking electro-magnet associated with said relay, a circuit for said unlocking electro-magnet including the relay 40 contacts, and additional contact mechanism controlled by the clock train to close said unlocking circuit after a period of closure of the secondary circuit by said relay, energization 45 of said unlocking electro-magnet causing unlocking of the relay and reopening of the secondary circuit. 50

In witness whereof, I hereunto subscribe my name this 19th day of February, A. D. 1920.

ALFRED L. SOHM.
